US0D1075199S

(12) **United States Design Patent** (10) **Patent No.:** **US D1,075,199 S**
(45) **Date of Patent:** **** May 13, 2025**

(54) **VACUUM CLEANER**

(71) Applicant: **Yingmei Hu**, Dongguan (CN)

(72) Inventor: **Yingmei Hu**, Dongguan (CN)

(**) Term: **15 Years**

(21) Appl. No.: **29/912,639**

(22) Filed: **Sep. 21, 2023**

(51) **LOC (15) Cl.** **15-05**

(52) **U.S. Cl.**

USPC **D32/18**

(58) **Field of Classification Search**

(57) **CLAIM**

The ornamental design for a vacuum cleaner as shown and described.

DESCRIPTION

FIG. 1 is a perspective view of a vacuum cleaner showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dash-dash broken lines in the drawings depict portions of the vacuum cleaner that form no part of the claimed design.

1 Claim, 8 Drawing Sheets
